UNITED STATES PATENT OFFICE

94,318

DESIGN FOR A LIFT BRIDGE

Joseph B. Strauss, San Francisco, Calif.

Application April 9, 1934, Serial No. 51,363

Term of patent 7 years

To all whom it may concern:

Be it known that I, Joseph B. Strauss, a citizen of the United States of America, residing at San Francisco, in the county of San Francisco and State of California, have invented a new, original, and ornamental Design for Lift Bridges, of which the following is a specification, reference being had to the accompanying drawing, forming a part thereof.

Fig. 1 is a front elevation of my new design.
and

Fig. 2 is a side elevation of the same.

I claim:—

The ornamental design for a lift bridge substantially as shown.

JOSEPH B. STRAUSS.
